UNITED STATES PATENT OFFICE.

CARL A. PFANSTIEHL, OF WAUKEGAN, ILLINOIS, ASSIGNOR TO PFANSTIEHL COMPANY, INC., OF NORTH CHICAGO, ILLINOIS, A CORPORATION OF NEW YORK.

ELECTRIC FURNACE.

1,273,920.

Specification of Letters Patent. Patented July 30, 1918.

Application filed November 19, 1914. Serial No. 872,953.

To all whom it may concern:

Be it known that I, CARL A. PFANSTIEHL, a citizen of the United States, residing at Waukegan, in the county of Lake and State 5 of Illinois, have invented certain new and useful Improvements in Electric Furnaces, of which the following is a full, clear, concise, and exact description, reference being had to the accompanying drawings, forming a part of this specification.

My invention relates to electric furnaces. One particular object of my invention is to provide a furnace adaptable for use in sintering ingots of tungsten metal in the process of producing ductile tungsten. My improved sintering furnace makes it possible quickly and economically to sinter a tungsten ingot by a single heating operation in a single furnace, and this is accomplished 20 without wasting any portion of the ingot under treatment.

In one of the best processes of the prior art it has been customary to sinter ingots of compressed tungsten powder in two operations; first in a tube furnace in which a fairly high degree of heat is employed, and later in a bell or bottle in which a heavy current is passed through the tungsten ingot. The electric current is used in heating the 30 ingot because that is the most feasible way in which to bring it to the requisite high temperature. The bell or bottle is employed in order that the tungsten may be heated in an atmosphere of hydrogen, for tungsten 35 when heated to a very high temperature in the air will oxidize rapidly. In these sintering furnaces of the prior art the upper end of the ingot is clamped in a water cooled terminal, fixed in position. The lower end 40 of the ingot is clamped in a copper terminal which floats in a bath of mercury, the current being conveyed to or from the lower terminal through the mercury. There is necessarily a large surface of contact between the lower terminal and the mercury, 45 in order to convey the heavy current employed. The lower terminal is made to float in the mercury in order to permit the lower terminal to move from side to side, or up or down, to a slight degree, as may 50 be necessary to accommodate the movements of the lower end of the ingot. The lower or free end of the ingot tends to move up or down due to the expansion or contrac-

tion of the metal when heated and cooled, 55 and there may be some sidewise movement due to the warping of the ingot when heated. If the lower terminal were not free to accommodate itself to these movements the ingot would in all likelihood be broken 60 when heated. It is necessary in these furnaces of the prior art to water cool the mercury bath and to supply hydrogen to the bell or bottle which surrounds the mechanism previously described. 65

These elaborate devices and precautions are provided because while it is necessary to heat the ingot to an extremely high temperature, the ingot has very little mechanical strength and cannot safely be subjected 70 to strains while undergoing the sintering operation.

While the sintering furnace above described is designed with the idea of reducing to a minimum the strains imposed upon 75 the ingot, it has still been necessary to heat the ingot at a moderate temperature and for a considerable period of time in order to give it sufficient strength to permit of its being handled in the sintering furnace 80 above described. Furthermore it has been impossible even with this elaborate furnace of the prior art to bring the ingot even in its final treatment to a temperature close to that at which the tungsten will fuse, because at or extremely near the fusing point 85 the tungsten does not have sufficient strength to support its own weight or to withstand even the slight strains imposed upon it by the terminal mechanism of the sintering furnace above described. 90

In these sintering furnaces of the prior art a considerable part of each end of the tungsten ingot is clamped within the terminals. The ends of the ingot are not, therefore, heated to a high temperature, as a result of which the ends of the ingot are not effectively sintered and must, therefore, be cut or broken off and wasted. 95

Under my improved process as carried 100 out in the sintering furnace hereinafter described in detail, the tungsten bar or ingot under treatment is heated from end to end and to a higher temperature than has heretofore been attained. Furthermore a single treatment in one sintering furnace takes 105 the place of treatment in two furnaces under the prior practice. The ingot treated

in my improved sintering furnace is workable in its entirety. There is no waste, and the higher temperature at which the ingot is sintered aids in producing a malleable 5 or more ductile product.

Broadly the sintering furnace hereinafter described and claimed comprises a heating chamber within which is disposed a cradle adapted to support an ingot under treatment. The cradle referred to is in the form 10 of a pair of ductile tungsten rods of fibrous structure and arranged horizontally and parallel with one another, connected in an electric circuit when an ingot supported by 15 the cradle is undergoing treatment.

My improved sintering furnace is more fully set forth in the following detailed description in which reference is made to the accompanying drawings, in which:—

20 Figure 1 is a longitudinal sectional view of the sintering furnace of my invention, the electrical connections being diagrammatically illustrated;

25 Fig. 2 is a fragmentary cross-sectional view taken on the line 2—2 of Fig. 1 and looking in the direction indicated by the arrows;

30 Fig. 3 is a view taken on the line 3—3 of Fig. 1 and looking in the direction indicated by the arrows, and

35 Fig. 4 is a fragmentary sectional view illustrating a slightly modified embodiment of my invention.

Similar reference numerals refer to similar parts throughout the several views.

Referring to the drawings, it will be seen that the sintering furnace of my invention comprises an alumina or alundum tube 10 provided with an outer sheath 11 of steel 40 and constituting the heating chamber of the furnace. The tube 10 and its sheath 11 extend through and are supported by a box or container 12 which is filled with a quantity of silica sand or other refractory material 13. A system of piping indicated at 28 extends through the body of silica sand 13. Cooling water is supplied to this piping at 29 and flows out at 30, a valve being provided, as indicated, to regulate the rate at 50 which heat is withdrawn from the walls of the tube 10 and its sheath 11.

Located in each end of the alumina or alundum tube 10 is a brass connector, said brass connectors being illustrated at 14 and 55 15 respectively. The connector 14 is substantially semi-circular in cross-section and is provided with a substantially U-shaped passage 16 the legs of which are arranged to be connected with a suitable source of 60 cooling water whereby the connector 14 may be kept cool. Water circulating through the passage 16 maintains the connector 14 at so low a temperature that the metallic connecting parts and conductors are not endangered 65 by the high heat developed within the heat-

ing chamber of the furnace. Secured to the brass connector 14 by screws or otherwise is a suitable copper connector 17 arranged to be connected with the source of electric energy supply.

70 The connector 15, like the connector 14, is substantially semi-circular in cross-section and is provided with a passage 18 through which water may be circulated to keep the connector 15 sufficiently cool. The connector 15, however, differs from the connector 14 in that it is provided with a sliding terminal 19 having dove-tailed sliding connection with the connector 15, as is clearly illustrated in Fig. 2. This construction permits 80 the rods 21 to expand and contract with changes of temperature and without warping. Upon the right end of the sliding terminal 19 (Fig. 1) is mounted a connector 20 arranged to be electrically connected with 85 the source of electricity supply.

Formed in the inner end of the brass connector 14 is a pair of apertures into which extend the ends of a pair of parallel horizontal tungsten rods 21 which, as will presently be made apparent, form a cradle for the tungsten ingot to be sintered. Suitable set screws, one of which is illustrated at 22, may be provided to retain the ends of the tungsten rods 21 in the connector 14, as 90 illustrated. The right ends of the tungsten rods 21 (Fig. 1) are fitted in apertures formed in the left end of the sliding terminal 19, the rods 21 being secured in the sliding terminal by suitable set screws 100 23, as is most clearly illustrated in Fig. 2. The rods 21 are conveniently circular in cross-section and are formed of ductile metallic tungsten wire which has been swaged, hammered or drawn to give it a 105 high tensile strength and a fibrous structure. In order to lend additional support to the ductile tungsten rods 21 I provide a pair of transverse supporting rods 24 of ductile tungsten which bear in the alumina 110 or alundum tube 10, as is most clearly illustrated in Fig. 3. The tungsten rods 24 are, of course, slipped into position before the sheath 11 is placed around the refractory tube 10.

115 During the sintering operation it is desirable that hydrogen be admitted to the heating chamber, and therefore I provide a hydrogen inlet pipe, illustrated at 25. This hydrogen inlet pipe is arranged to be connected by any suitable means with a source of hydrogen supply. During the sintering operation it is necessary to close the ends of the refractory tube 10 and therefore I provide a pair of semi-circular blocks, one 120 of which is indicated at 26 and the other of which is indicated at 27, these blocks being disposed in the positions shown during the heating operation. The block 27 is desirably provided with an opening at 27^a 125

closed by a mica window 27^b through which the heating of the rods and the ingot may be observed. The block 27 may conveniently be provided also with a small pipe 27^c through which the hydrogen may escape from the furnace chamber. The operator ordinarily lights the hydrogen at the end of the pipe 27^c in order that the flow of the gas may be indicated. The connector 14 and 5 the sliding terminal 19 are electrically connected with the terminals of the secondary winding of a suitable alternating current transformer, as illustrated, the primary winding of the transformer being electrically connected with a generator, as suitable alternating current supply. In the primary circuit is preferably included a regulating rheostat in order that any desired current may be supplied to the furnace heating elements, *i. e.* the tungsten rods 21. Experience indicates that good results can be obtained when each of the supporting and heating rods 21 has a cross-sectional area substantially one-half that of the ingot to be sintered. In sintering ingots of from $\frac{1}{8}$ to $\frac{1}{16}$ of an inch square I have found it expedient to employ supporting and heating rods 21 of circular cross-section, approximately $\frac{1}{16}$ of an inch in diameter. 10

20 In the use of the sintering furnace of my invention an ingot of compressed tungsten powder is placed upon the cradle formed by the parallel tungsten rods 21. The compressed tungsten ingot, preferably prepared by employing the method disclosed in my co-pending application, Serial No. 39,500, filed July 12, 1915, and preferably of square or rectangular cross-section, is disposed upon the rods 21, as is most clearly illustrated in 25 Figs. 2 and 3. A current of electricity is now passed through the tungsten rods 21, heating them to incandescence. Part of the current will be diverted from the tungsten rods and flow through the ingot. The tungsten rods 21, having been swaged, hammered, drawn or otherwise treated to give them a fibrous structure of great strength and rigidity, will not when heated tend to sag to the same extent as will the ingot, the tungsten cross rods 24 coöperating also to prevent undue sagging of the cradle. In sintering an ingot substantially $\frac{1}{8}$ of an inch by $\frac{1}{8}$ of an inch in cross-section, I have found that a current of from 1100 to 1200 amperes, 30 passing through two cradle rods each approximately $\frac{1}{16}$ of an inch in diameter will heat the ingot almost to the fusing point. During the heating operation hydrogen is passed into the furnace chamber to prevent 35 oxidization.

I am unable to explain the precise reason that the tungsten ingot is heated to fusion by the passage of electricity through the members of the cradle, without the cradle members being heated to such an extent that

they melt or seriously sag. I attribute this, however, principally to the fact that in the process of compression the tungsten ingot, which is made up of finely divided tungsten, a great amount of latent heat is stored in the 40 ingot, which heat manifests itself in mechanical action when the ingot has been raised to such a temperature as to allow the deformed particles to move upon one another due to their internal stress. It may 45 be that the fact that the tungsten ingot apparently heats to a higher temperature than the cradle upon which it is supported is due in part to the rapid dissipation of heat from the members of the cradle into the water 50 cooled terminals at the ends thereof. The ingot, being in poor heat conducting union with the cradle members, does not dissipate its heat so rapidly to the water cooled terminals, and therefore acquires a higher temperature than does the cradle by reason of the electric current which actually passes through the ingot. I am not certain that either of these explanations is the correct one, but I do know that the construction described herein accomplishes the satisfactory 55 sintering of the ingot without melting the supporting cradle.

In Fig. 4 I have illustrated in fragmentary section a slightly modified embodiment 60 of my invention wherein an alumina or alundum tube is illustrated at 50. The refractory tube 50 is not provided with a steel sheath as is the tube 10 illustrated in Fig. 1, and therefore I find it desirable to 65 glaze the tube 50 on its outer surface to prevent the escape of hydrogen from the heating chamber. In other respects the form of sintering furnace illustrated in Fig. 4 is 70 similar to the furnace illustrated in Figs. 1 to 3, inclusive, and the several parts of the furnace illustrated in Fig. 4 have been given the same reference numerals as the corresponding parts illustrated in Figs. 1, 2 and 3.

Before hydrogen is admitted to the furnace heating chamber as previously described, it is thoroughly purified by one of the processes commonly employed by persons skilled in the art to which my invention appertains. I do not deem it necessary 75 to illustrate or describe in the present application the apparatus or process whereby commercial hydrogen is purified to adapt it for use in my improved furnace.

I have illustrated the furnace of my invention provided with but a single pair of cradle rods 21. It will be apparent that additional rods may be supplied. Thus three parallel rods will support two ingots and four rods will support three ingots, et 80 cetera. The number of supporting rods and their cross-sectional shape may be varied to suit the particular purposes to which the furnace is to be applied.

Having described one embodiment of my 85

invention in some detail it will be apparent that it has several advantages: first, the ingot to be sintered is not subjected to any mechanical stress or strains and may for 5 this reason be heated to a higher temperature than would be feasible in the furnaces of the prior art; second, the furnace is extremely simple in its construction and in 10 operation; third, the whole length of the ingot is heated to the high temperature required for successful sintering, and there is, therefore, no waste; fourth, it is possible to observe closely what is going on within the furnace at all times; and fifth, the heating 15 and cooling of the cradle and the ingot may be closely regulated and controlled.

Having now described my invention, what I claim as new and desire to secure by Letters Patent of the United States is:

20 1. An electric furnace for sintering ingots of compressed metallic tungsten powder at or near its fusing temperature comprising in combination a heating chamber of refractory material, a pair of terminal blocks, one at either end of said chamber, a cradle of ductile metallic tungsten of fibrous structure extending horizontally from one terminal block to the other and adapted to support an ingot of compressed tungsten 25 powder in intimate contact with the cradle throughout the length of the ingot, and means for passing through said cradle from terminal block to terminal block a current of electricity sufficient to raise the temperature of the cradle substantially to the fusing 30 point of metallic tungsten.

2. An electric furnace for sintering ingots of compressed metallic tungsten powder at or near its fusing temperature comprising in 40 combination a heating chamber of refractory material, a pair of terminal blocks, one at either end of said chamber, a cradle of ductile metallic tungsten of fibrous structure extending horizontally from one terminal 45 block to the other and adapted to support an ingot of compressed tungsten powder in intimate contact with the cradle throughout the length of the ingot, means for passing through said cradle from terminal block to terminal block a current of electricity sufficient to raise the temperature of the cradle substantially to the fusing point of metallic tungsten, and regulable means for cooling 50 the walls of said heating chamber.

55 3. A furnace of the class described comprising a cradle formed by a pair of parallel rods arranged to support in electric contact therewith a conducting ingot to be sintered, and means for passing an electric 60 current through said cradle and ingot to heat the cradle and sinter an ingot carried thereby.

4. A furnace of the class described comprising a cradle formed by a pair of parallel rods of ductile tungsten of fibrous struc-

ture adapted to support in electric contact therewith an ingot to be sintered, and means for passing an electric current through the cradle and ingot to heat the cradle and sinter an ingot carried thereby.

5. A furnace of the class described comprising a heating chamber, a cradle within said heating chamber, said cradle comprising a pair of parallel rods of ductile metallic tungsten of fibrous structure arranged to support an ingot of compressed powdered tungsten to be sintered, and means for connecting said rods with a source of electric energy supply.

6. A furnace of the class described comprising a heating chamber, a cradle within the heating chamber, said cradle comprising a pair of parallel rods arranged to support a conducting ingot to be sintered, and means for connecting, said rods with a source of electric energy supply.

7. A furnace of the class described comprising a heating chamber, a pair of terminals arranged to be connected with a source of electricity supply, and a pair of horizontal parallel rods of ductile tungsten interposed between said terminals and constituting a cradle for an ingot to be sintered.

8. A furnace of the class described comprising a heating chamber, a pair of terminals disposed one at each end of the heating chamber, said terminals arranged to be connected with a source of electricity supply, a pair of rods interposed between said terminals constituting a cradle to support an ingot to be sintered, and means for maintaining an atmosphere of hydrogen within said heating chamber during the heating operation.

9. A furnace of the class described comprising a heating chamber, terminals at either end of said heating chamber, means for passing cooling water through said terminals, a tungsten cradle interposed between said terminals, said cradle arranged to support an ingot to be sintered, and means for connecting said terminals with a source of electricity supply.

10. A furnace of the class described comprising a refractory tube constituting a heating chamber, a pair of terminals disposed within the refractory tube, a cradle of ductile tungsten interposed between said terminals, means for maintaining an atmosphere of hydrogen within the heating chamber, and means for connecting said terminals with a source of electricity supply.

11. A furnace of the class described comprising in combination a refractory tube constituting a heating chamber, a pair of terminals one at each end of the refractory tube, means for passing cooling water through each of said terminals, a pair of rods of ductile metallic tungsten of fibrous structure interposed between said terminals,

said rods constituting a cradle to support an ingot to be sintered, means for maintaining an atmosphere of hydrogen within the heating chamber during the sintering operation, and means for connecting said terminals with a source of electricity supply.

In witness whereof I have hereunto sub-

scribed my name this 7th day of November, A. D. 1914.

CARL A. PFANSTIEHL.
